UNITED STATES PATENT OFFICE.

GUSTAV H. KLOEHS, OF PHILADELPHIA, PENNSYLVANIA.

CIPHERLESS DEVICE FOR PIPE ORGANS.

Application filed February 6, 1924. Serial No. 690,958.

My invention relates to improvements in pipe organs, and it consists of the constructions, combinations and arrangements herein described and claimed.

An object of the invention is to provide a device for eliminating ciphers should such occur in the playing of a pipe organ, a so-called cipher consisting of the continued sounding of one of the pipes by reason of an obstruction preventing the seating of the felt button by means of which the passage of air to said pipe is controlled.

A further object of the invention is to provide a device by which an entire chest may be thrown out of action should one of the pipes in said chest continue to sound and thereby produce a cipher during the playing of the organ.

A further object of the invention is to provide a cipherless device which is capable of operation during the playing of the organ to produce a rapid oscillation of air in any one of the chests of the organ to clear such chest of an obstruction which may be producing a cipher.

Another object of the invention is to provide a so-called cipherless device for each chest action of a pipe organ each of which is capable of individual operation for the purpose of either cutting out the entire chest with which it is associated or producing an oscillation of air therein to clear it of an obstruction which may be producing a cipher in one of the pipes of that chest.

A further object of the invention is to provide a plurality of cipherless devices, one for each chest action of a pipe organ, the electric controlling means of said devices being operable either individually or in multiple so that only one or more than one (should the occasion ever warrant doing so) of the cipherless devices may be brought into play to cut out the associated chest action.

A further object of the invention is to provide a cipherless device for the purposes described which is of such a construction that it may readily be separated, thereby making the vital working parts immediately accessible should any fault in operation be discovered.

A further object of the invention is to provide a cipherless device for each chest action in a pipe organ, each cipherless device being in the nature of an electropneu-

matic valve interposed between the main air supply conduit and the associated chest action.

Other objects and advantages will appear in the following specification, reference being had to the accompanying drawings, in which:

Fig. 1 is a diagram illustrating the application of a cipherless device to each of a plurality of chest actions,

Fig. 2 is a sectional view showing the cipherless device applied to one of the chests of a pipe organ and showing the parts in normal operating positions, the view being a composite of sections taken on the lines 2—2 of Fig. 1 in order that the air paths may more readily be followed,

Fig. 3 is a view similar to Fig. 2 illustrating the action upon the occurrence of a cipher,

Fig. 4 is a front elevation of the cipherless device, the cover plate being removed to show the release electro-magnets,

Fig. 5 is a perspective view of the pneumatic puff, also showing the cut-out and escape valves carried thereby,

Fig. 6 is a perspective view of the magnetic release valve, and

Fig. 7 is a detail perspective view of the release electro-magnets.

Reference may be had to my co-pending application No. 1, relating to organ pipe controls, filed Feb. 6th, 1924, Serial No. 690,957, for a complete illustration and description of the key-board and relay mechanism by which the electro-magnets of the chest action are operated. The relay mechanism is omitted from disclosure in this application, but a portion of the keyboard and of the chest action is duplicated in order that the reader might more readily understand the manner of co-operation therewith of the so-called cipherless device.

This statement is not intended to carry the inference that the cipherless device must be inseparably identified with the particular chest action disclosed. The cipherless device will operate in any organ having one or more chest actions, and in respect to each of these, it will function alike.

The organ pipe control or as much thereof as is disclosed in this application, comprises a keyboard of which only three keys 1, 2 and 3, are diagrammatically shown in Fig.

1. These keys may also be regarded as those producing the notes C, D and E in the corresponding organ pipes 4, 5 and 6.

Associated with the respective pipes 4, 5 and 6 are control electro-magnets 7, 8 and 9. These are in circuit with the respective keys so that when any one of the keys is depressed, the corresponding control magnets will respond by the lifting of a flap valve which in turn causes the sounding of the corresponding pipe. The flap valves are designated 10, 11 and 12.

The electrical circuit just spoken of, comprises a battery 13 which has a common wire connection 14 with a series of contacts 15, 16 and 17 below contactors 18, 19 and 20 of the respective keys 1, 2 and 3. The respective contactors are connected by wires 21, 22 and 23 with one side of each of the respective control magnets 7, 8 and 9. The other side of each of the magnets is connected by means of a wire 24 to the common return wire 25. The reader will see at once that a depression of the key 1 will close a circuit which flows as follows: Positive side of the battery 13 over wire 14, past contact 15 and contactor 18 to the wire 21, through the electro-magnet 7 and over wires 24 and 25 to the negative side of the battery 13.

30 The resulting energization of the electro-magnet 7 attracts the flap valve 10. The pole pieces of the magnet extend through the lead base 26 of the valve chest 27. The valve chest has a threaded boss 28 in which 35 a short vent tube 29 is screwed. The valve 10 covers the vent tube when the electro-magnet 7 is de-energized. Upon energization of the electro-magnet the vent tube 29 is uncovered so that there may be an escape 40 of air from the duct 30 which offers communication between the valve chest and the puff 31. Upon the escape of air at the vent 45 29, the puff 31 collapses so that the felt and leather buttons 32 and 33 uncover the orifice 34 permitting air to enter the pipe 4 from the primary air passage 35 and cause the sounding of the note C.

50 A depression of any other one or combination of the keys on the keyboard will produce the identical effect in respect to corresponding control magnets so that any one or combination of the organ pipes will sound. Under normal conditions, i. e., when all of the keys are in the raised position, no sound 55 will issue from the organ pipes inasmuch as the various felt and leather buttons are held up in the various orifices 34 by means of springs 36 which press beneath the leather part of the puff 31. The springs hold the 60 buttons in the closed position when there is an equalization of air pressure from the passage 35 on each side of the puff. Air from the passage 35 passes down through the opening 38 in which the electro-magnet 65 7 (for example) is situated, through ports

39 and 37 in the lead base 26, into the air chest 27 and through the duct 30 into the puff 31. Upon energization of the magnet 7, the flap valve 10 is attracted against the base 26 so that a closure of the port 39 and 70 a cutting off of air from the duct 38, follows.

Air from the puff 31 now escapes through the duct 30 and vent 29 to atmosphere, and by virtue of the superior air pressure in the 75 passage 35, the puff 31 and spring 36 will collapse, causing an uncovering of the orifice 34. Air from the passage 35 now sounds the note C in pipe 4 as already explained. The flap valve 10 is loosely held by a link 40 which attaches to the valve chest 27 at a convenient place. The vent tube 29 is adjustable. For this purpose it has a screw driver slot 41 by means of which the vent tube may be turned in or out in the boss 28 80 so that the valve will respond more or less promptly to the energization of the electro-magnet above.

It sometimes occurs in the playing of the organ that an obstruction will enter the space between the leather button 33 and the upper side of the primary air passage 35 and thereby prevent the button from seating. Such obstruction may consist of a roll 85 of lint, dust, etc. The effect is that air continues to pass through the orifice 34 so that the corresponding organ pipe continues to sound, regardless of the fact that the key which controls it has long been released. The continued droning of the sounding pipe 90 spoils the music and this to the extreme discomfiture of the musician. Inasmuch as the closure button 32 is not easily accessible, it becomes necessary to stop playing the organ until a mechanician can be secured. 95 This usually means that the use of the organ must be dispensed with either for the remainder of the service or throughout an entire performance, depending on whether the organ is installed in a church or theatre. 100

105 The cipherless device is operable in such a manner as to either clear any obstructed button so that it may reseat over the organ pipe orifice, or if this is not possible, then to cut out that chest in which the defective 110 pipe is situated. In a large organ having numerous chest actions, the use of one chest may readily be dispensed with in an emergency. It is better to dispense with one chest action than to shut down the entire 115 organ. It should have been explained that the obstruction of the closure button and the consequent continued sounding of the corresponding pipe is known as a "cipher". It is by virtue of the fact that the invention 120 is capable of eliminating ciphers that it is called a cipherless device.

125 Figure 1 illustrates two separate chest actions 42 and 43. The pipes 44, 45 and 46 are for the purposes of this description con-

trolled by keys other than those which control the pipes of the chest 42. The chest 43 is identical with the chest 42 in so far as the mechanism is concerned, and as the operation of one of the pipes (key of C) has already been described, it is unnecessary to go into detail in respect to any one of the pipes in the chest 43. It is sufficient to say that each chest has its own cipherless device.

10 And again, inasmuch as each cipherless device is alike, the description of one will suffice for all.

A rectangular box, composed of a bottom 47, top 48, sides 49 and 50, back 51 and front 15 cover 52, furnishes the housing for a cut-out valve 53 and the magnetic release valve 54. It also houses a puff 55 which, by means of a washer 56 and nut 57, carries a rod 58 on which the cut-out valve 53 is mounted.

20 This rod also carries the escape valve 59 which is situated on the outside of the box.

Air under compression is present in the chamber defined by the walls of the cipherless box. This air is admitted by a pipe 60 which communicates with the main air supply conduit 61 (Figs. 1 and 4). The reader may consider this chamber as being filled with compressed air at all times. It is this compressed air that passes on to the primary 25 air passage 35 (Fig. 1) and furnishes the means for the sounding of the organ pipes. The air is conducted to this passage by the direct application of the cipherless device to the side of the chest action as shown in 30 Fig. 2. As long as the operation of the chest action is normal, i. e., all of the orifice control buttons 32 and 33 seat properly upon release of the corresponding organ keys, the cipherless device will permit the passage of 35 air from the conduit 61 to the primary air passage 35.

This is primarily accomplished by the cut-out valve 53. The area of the puff 55 being greater than that of the valve 59, the pressure of compressed air within the cipherless 40 chamber will press up on the puff so as to raise the valve 53 to the position in Fig. 2. The passages 64 and 65 in the bottom 47 are thereby held open to communication with the interior of the chest action so that a supply of air in the passage 35 may be had. This same action of the puff 55 holds the escape valve 59 closed against the bottom of 45 the passage 64 so that none of the air from the chamber may escape.

Let the reader imagine the occurrence of a cipher. As explained above, this means that the button 33 (for example) has not seated and that the key of C continues to sound. The organist knows by the sound 50 of the particular pipe ciphering which one of the various chest actions requires attention. He has before him a series of switches 66, 67, etc., one for each chest action involved.

Each switch controls one of the cipherless devices. A battery 68 has a positive wire 69 which is common to all of the switches or contactors. The contactor 70 of the first switch has a wire 71 which connects to one side of a release magnet 72 in the cipherless chamber. It is this magnet that controls the release valve 54. A wire 73 from the other side of the magnet has connection with a common negative return wire 74 which joins the negative pole of the battery 68. It is easy to see that the depression of the switch 66 (for example) will close a circuit through the release magnet 72 so that the valve 54 is lifted and passages 75, 76, 77 and 78 and the space above the puff 55 are opened to the interior of the cipherless device. The same action of the magnet 72 will close the bottom of the passage 75 by virtue of the escape valve 79 being carried by the same stem 80 which carries the magnetic release valve 54.

Attraction of the valve 54 permits an immediate imposition of air pressure on top of the puff 55, whereupon there will be a temporary equalization of air pressures in the cipherless chamber and in the space above the puff. The weight of the valves 53 and 59, together with the rod 58, now becomes an element in causing a reversal of positions of the valves 53 and 59 so that instead of the valve 53 being supported as in Figure 2, it now becomes seated on the passage 64 as shown in Figure 3, and upon becoming so seated is held firmly in that position by the air pressure in the chamber above. This condition remains as long as the organist keeps the switch 66 closed.

The closure of the cut-out valve 53 is attended by an escape of air from both the primary and secondary passages 35 and 37 by virtue of the valve 59 uncovering the bottom of the passage 64 (Fig. 3). Immediately upon release of the switch 66 the attendant deenergization of the magnet 72 will permit the release valve 54 to fall and the pressure on top of the puff 55 to seek release to atmosphere at the valve 79.

Superior pressure of air in the cipherless chamber again presses upward on the puff 55, opens the valve 53 and closes the valve 59 so that a charge of air enters the passage 35 through the conduit 65. A number of rapid operations of the switch 66 will cause rapid oscillations of air in the passage 35 so that if the obstruction beneath the button 33 is of a light nature, it can readily be blown out so that the button may re-seat.

If the obstruction is of such a nature that this expedient will not work, the organist may leave the switch 66 closed so that the cipherless device remains in the condition shown in Figure 3, and the chest action which it controls remains cut out through the rest of the performance. As already

stated, it is only that one of the cipherless devices in respect to which the electric switch is closed that assumes a cut out condition. The other cipherless devices remain operative as in Fig. 2.

The removal of the cover plate 81 (Fig. 2) permits access to the interior of the puff 55. This cover plate closes an opening 82 which communicates with the space above the puff. 10 The cover plate is made of wood and is held in place by any suitable means, for example, screws 83. The cut-out valve 53 is composed of a leather disk 84 and a pair of felt disks, of which one is thicker than the other, adapted for the purpose of seating over the passage 64. The escape valve 59 has similar felt disks for a similar purpose, these being carried by a leather disk 85. The various disks of the respective valves are held in 15 place by leather buttons 86 and 87 respectively.

These buttons are either held on the rod 58 by friction alone, or if it be so desired, the rods may be threaded as in the case of 20 the valve stem 80 so that adjustments of the leather buttons may be made by turning them along the threads. In respect to the valve stem 80, the leather button 88 is adjustable on the stem by means of the threads 25 shown. The buttons support the small escape valve which is but loosely held on the stem. This valve is composed of leather and felt washers or disks, the felt coming next to the passage 75.

35 The magnetic release valve 54 is composed of a thin metallic disk 89 which is fixedly mounted on the stem 80. A felt disk 90 is secured beneath the metallic disk so as to make a tight joint with the bottom 47 when 40 the valve is seated as in Fig. 2. The pressure of air in the cipherless chamber holds the magnetic valve seated. A disk of kid is pasted on top of the disk 89 so that the magnetic valve will not stick to the poles of the 45 release magnet 72 when attracted in the position shown in Fig. 3. In order that the rod 58 of the cut-out and escape valves 53 and 59 may be guided, provision is made of a bracket 92 through which the exposed 50 end of the rod passes as clearly shown in Fig. 2.

Attention is directed to Figs. 1, 2 and 4. It is to be observed that the front cover 52 is secured over the cipherless chamber by 55 means of wood screws 93. In Fig. 2, the base 51 is fastened to the cipherless box by wood screws 94. In Fig. 4, the bottom 47 is fastened to the sides 49 and 50 by wood screws 95 and the top 48 is secured to the 60 sides by wood screws 96. The reader will understand at once that this manner of construction of the cipherless device permits the easy removal of any part, thereby making the interior of the device immediately 65 accessible. This is one of the strong fea-

tures of the invention. An occasion may arise whereupon it becomes necessary to inspect the interior for any possible defect in any of the parts. Any particular part may be reached by merely removing such parts 70 of the box which are immediately adjacent thereto, and it is not necessary to take down the entire device before a needed repair can be effected.

The manner of making the electrical connections with the release magnet 72, is illustrated in Fig. 4. The wire 71 (Fig. 1) is suitably connected (by soldering, for example) with the contact piece 97 which extends through the side 50 to the interior of the 75 chamber where connection with one side of the magnet 72 is made. Similarly, the wire 73 (Fig. 1) is connected with a contact 98 in the side 49, the other end of the magnet winding 72 being connected to that part of 80 the contact which appears on the inside of the chamber.

The operation may be briefly reviewed to advantage. Refer to Fig. 1. The reader can readily imagine a keyboard composed of a great number of keys such as 1, 2 and 3, each of which for the purpose of this description has electrical connections for controlling a single organ pipe. For example, the key contact 18 controls the pipe 4 which is adapted to sound the note C. Similarly, the key contact 19 controls the pipe 5 adapted to sound the key D, and so on through all of the organ keys and 90 throughout the entire range of the instrument.

Various groups of organ pipes are collected in different chest actions, a certain group of pipes being collected in the chest 42, another group of pipes being collected 95 in the chest 43, and so on. The manner of and reasons for so grouping the pipes is immaterial in so far as the invention is concerned, it being the purpose of the invention to permit the exercise of such supervision over each individual chest action that any one may be entirely cut out without in 100 the least affecting the operation of the other chest actions.

It may do no harm to briefly repeat the 105 operation upon depressing one of the keys. Take the key 1: Upon depressing this key a circuit through the control magnet 7 is closed so that the flap valve 10 is attracted and the vent 29 opened to permit the escape of air from beneath the puff 31 through the duct 30.

The attendant release of pressure permits the superior air pressure in the primary air passage 35 to displace the buttons 32 and 33 so that compressed air escapes at the orifice 34 into the pipe 4 and causes the sounding of the note. Under normal conditions, the flap valve 10 is seated on the vent 29 so that air from the primary air passage 110

35 may pass through the port 39 into the duct 30 and so into the puff chamber 31 to hold the control button up against the orifice 34.

5 It occasionally happens that a roll of dust or lint in the primary air passage 35 will find its way between the control buttons and the inlet to the orifices 34. Such obstruction will prevent the control button from seating so that the particular pipe continues to sound, notwithstanding the fact that the organist has released the key which controls it. This continued sounding of a pipe is called a cipher, and it is the purpose of the invention to remove the cause of the cipher, if possible, and if this is not possible, then cut out the entire chest action so that the music is not spoiled by the droning of the pipe in question.

10 The cipherless device controls the passage of air from the main air supply conduit 61 to a particular chest action. The cipherless device is in the nature of an electro-pneumatic valve. The cipherless device, under 15 normal conditions, permits the flow of air into the chest action, and it is capable of such control as to entirely cut off the flow of air. The flow of air occurs from the conduit 61 through pipe 60 into the chamber of 20 the cipherless device, through passage 64 (Fig. 2) to the primary air passage 35. The pressure of air in the cipherless chamber holds the puff 55 up so that the cut-out valve 53 is held raised and the escape valve 25 59 is held up against the bottom of the passage 64 so as to prevent the escape of air at that place. The magnetic release valve 30 54 is seated on the passage 75 so that no air may reach the space above the puff 55 through passages 35, 36 and 37.

35 It will be understood at once that as long as the cut-out valve 53 (Fig. 2) remains raised, the communication between the chest action and the interior of the cipherless device will be maintained. Imagine the occurrence of a cipher, in respect to one of the pipes in the chest action 42. The organist knows in which of the chests the cipher is occurring. He has before him a series of 40 switches 66, 67, etc., of which one controls a corresponding chest action. He should depress the switch 66. This will complete an electrical circuit through the release magnet 72. The attraction of the magnet will raise the magnetic release valve 54 so that the bottom of the passage 75 is closed by the valve 79 and the other passages 35, 36 and 37 are opened to the interior of the cipherless device.

45 Consequently, there is an equalization of pressure on each side of the puff 55, permitting the valves 53 and 59 to fall by gravity so that they assume the position shown in Fig. 3. The opening of the valve 59 permits 50 the escape of air from both the passages 35

and 37, and the pressure of the air in the cipherless chamber now imposes all of its weight on top of the valve 53 and on top of the puff 55 so that the position in Fig. 3 is maintained as long as the organist leaves 55 the switch 66 closed. This, in fact, he will do if he desires to cut out the chest action 42 entirely.

55 Ordinarily, however, this will not be necessary, and in fact, not desirable, because 60 those pipes in the chest action 42 may be necessary for the desired rendition of a musical selection. The organist will therefore resort to the expedient of rapidly opening and closing the switch 66. This, the reader 65 can readily understand, will cause a rapid oscillation of the valves 53 and 59, as well as the valves 54 and 79, ultimately producing a succession of air impulses in the primary air passage 35 and thereby probably blow out 70 any obstruction which may be holding one of the control buttons 33 open. It is therefore apparent that the cipherless device has two important functions: one, to eliminate a cipher should such occur and two, to permit 75 the entire cutting out of a chest action in which it may be found that a cipher cannot be eliminated by the means described.

80 While the construction and arrangement of the improved cipherless device for organs as herein described and claimed, is that of a generally preferred form, obviously modifications and changes may be made without departing from the spirit of the invention or 85 the scope of the claims.

90 While the construction and arrangement of the improved cipherless device for organs as herein described and claimed, is that of a generally preferred form, obviously modifications and changes may be made without 95 departing from the spirit of the invention or the scope of the claims.

100 I claim:—

105 1. An organ having an air passage provided with a pipe orifice, a button for controlling the flow of air into said orifice, a conduit for supplying the passage with air, a device interposed between the conduit and said passage through which the air must flow to reach the latter said device having a 110 cut-out valve which permits said flow of air, and a puff against one side of which the pressure of air in said device is exerted to sustain the cut-out valve in an open position.

115 2. An organ having an air passage provided with a pipe orifice, a button for controlling the flow of air into said orifice, a conduit for supplying the passage with air, a device interposed between the conduit and said passage through which the air must flow to reach the latter said device having a 120 cut-out valve which permits said flow of air, and a puff against one side of which the pressure of air in said device is exerted to sustain the 125

cut-out valve in an open position, and means for equalizing the pressure of air on both sides of the puff thereby permitting the valve to gravitate to a closed position.

3. An organ having an air passage provided with a pipe orifice, a button which is movable to control the flow of air into said orifice, a conduit for supplying the passage with air, a device interposed between said conduit and the passage through which air must flow to reach the latter said device including a passage adapted to communicate with the atmosphere, a puff carried in one position by air pressure on one side thereof, a rod carried by the puff and extending through said passage, and a pair of valves carried by said rod one covering the outer end of said passage the other being raised from the inner end of said passage when said puff is held as stated to permit the air to pass through said device.

4. An organ having an air passage provided with a pipe orifice, a button which is movable to control the flow of air into said orifice, a conduit for supplying the passage with air, a device interposed between said conduit and the passage through which air must flow to reach the latter said device including a passage adapted to communicate with the atmosphere, a puff carried in one position by air pressure on one side thereof, a rod carried by the puff and extending through said passage, a pair of valves carried by said rod one covering the outer end of said passage the other being raised from the inner end of said passage when said puff is held as stated to permit the air to pass through said device, and means adapted to admit air from the interior of said device to the other side of the puff to equalize the pressures thereon permitting the rod to fall and the position of said valves to be reversed thereby cutting off the flow of air through said device and permitting an exhaust of air through said passage.

5. An organ having an air passage provided with a pipe orifice, a button operable in said passage and against the orifice to control the flow of air into the pipe, and means for producing pulsations of air in said passage and through said pipe orifice to dislodge any obstruction which may be preventing the button from seating over the orifice.

6. An organ having an air passage provided with a pipe orifice, a button situated in said passage and adapted to move in respect to the orifice to control the flow of air thereinto, and an electro-pneumatic valve for controlling the flow of air to said passage said valve being adapted to produce pulsations of air in said passage and through said pipe orifice to dislodge any obstruction which may be preventing the button from seating.

7. An organ having a passage provided with a pipe orifice, a button situated in said passage which is movable in respect to the orifice to control the flow of air thereinto, a pneumatic valve for controlling the flow of air into said passage, and electrically operated means capable of oscillating the valve to produce pulsations of air in said passage and through said pipe orifice to dislodge any obstruction which may be preventing the button from seating.

8. A device of the character described having a chamber provided with a communicating conduit and a duct which communicates with the chamber at both ends, means to supply the chamber with compressed air which is adapted to flow out of the conduit, a puff situated in the chamber over one outlet of the duct, a valve carried by the puff and held in a lifted position in respect to the conduit by the depression of said puff under the compression of air, and a valve controlling the other end of the duct to prevent access of air pressure to the other side of the duct.

9. A device of the character described having a chamber provided with a communicating conduit and a duct which communicates with the chamber at both ends, means to supply the chamber with compressed air which is adapted to flow out of the conduit, a puff situated in the chamber over one outlet of the duct, a valve carried by the puff and held in a lifted position in respect to the conduit by the depression of said puff under the compression of air, a valve controlling the other end of the duct to prevent access of air pressure to the other side of the duct, and means to displace said valve to admit air to the other side of the puff.

10. A device of the character described having a chamber provided with a communicating conduit and a duct which communicates with the chamber at both ends, means to supply the chamber with compressed air which is adapted to flow out of the conduit, a puff situated in the chamber over one outlet of the duct, a valve carried by the puff and held in a lifted position in respect to the conduit by the depression of said puff under the compression of air, a valve controlling the other end of the duct to prevent access of air pressure to the other side of the duct, and means to displace said valve to admit air to the other side of the puff for the equalization of pressures permitting the first valve to move to a closing position over said conduit.

11. A device of the character described having a chamber provided with a duct communicating with the chamber at both ends and having a conduit communicating with the chamber and the atmosphere, a puff covering one outlet of the duct, means supplying the chamber with compressed air and

thereby collapsing the puff, a double valve for said conduit supported by the puff one valve closing the atmosphere side the other opening the chamber side so that air may flow through said passage, and a valve for the other end of said duct held in place by the pressure of air in the chamber to thereby prevent an equalization of pressures on each side of the puff.

12. A device of the character described having a chamber and being provided with a conduit furnishing communication between the chamber and atmosphere and having a duct communicating with the chamber at one end and at the other end with a passage one end of which communicates with the chamber the other with the atmosphere, a puff situated across the chamber end of the duct, means furnishing the chamber with compressed air to flow into the conduit, a double valve carried by the puff of which one closes the atmosphere side of the conduit and the other opens the chamber side when the puff is depressed by said compressed air, and a double valve in said passage of which one closes the chamber side to prevent equalization of air pressure on both sides of the puff the other being open to furnish outside air communication with the other side of the puff.

13. A device of the character described having a chamber and being provided with a conduit furnishing communication between the chamber and the atmosphere and having a duct communicating with the chamber at one end and at the other end with a passage one end of which communicates with the chamber and the other with the atmosphere, a puff situated across the chamber end of the duct, means furnishing the chamber with compressed air to flow into the conduit, a pair of valves carried by the puff of which one closes the atmosphere side of the conduit and the other opens the chamber side when the puff is depressed by said compressed air, a double valve in said passage of which one closes the chamber side to prevent equalization of air pressure on both sides of the puff the other being open to furnish outside air communication with the other side of the puff, and means to simultaneously raise said double passage valve to close the

atmosphere side and open the chamber side to thereby permit equalization of pressures on both sides of the puff and a reversal in 55 the position of the double valve in the conduit.

14. A device of the character described comprising an enclosure composed of bottom, top, side, base and cover plates, the top 60 having a passage opening toward the chamber defined by said parts, the base having a passage communicating between the chamber and the atmosphere and also having a conduit communicating between the chamber 65 and atmosphere, the cover plate having a passage affording communication between the top and base passages thereby defining a duct; a puff disposed over the chamber end of said duct, means furnishing the 70 chamber with compressed air and thereby depressing the puff, a double valve carried by the puff of which one member holds the chamber end of the conduit open for the passage of air and the other member holds the atmosphere end of the conduit closed, a double valve in said base passage of which one member holds the chamber end closed to prevent equalization of pressures on both 75 sides of the puff and the other member holds the atmosphere end of the passage open, and means by which the aforesaid parts of the enclosure are removably held together to permit access to any of the internal parts.

15. An organ comprising a chest action 85 having primary and secondary air passages, a puff having a control button situated in the former there being a duct furnishing communication between the secondary air passage and the space beneath the puff, a 90 vent valve, an electro-magnet for attracting the valve to sever communication between the secondary passage and said duct thereby permitting air pressure in the primary passage to depress the puff and move the control button, a conduit furnishing said passages with air, a cipherless chamber through which said air must pass to reach the passages, valve means in said chamber occupying one position to maintain the continuity 95 of air flow, and means for causing the reversal of said valve means to cut off the flow of air.
